US0D1067942S

(12) **United States Design Patent** (10) Patent No.: **US D1,067,942 S**
(45) Date of Patent: ** Mar. 25, 2025

(54) **DISPLAY SCREEN OR PORTION THEREOF WITH GRAPHICAL USER INTERFACE**

- (71) Applicant: **Caterpillar Inc.**, Peoria, IL (US)
(72) Inventors: **Keith Folken**, West Peoria, IL (US); **Mitchell B. Howard**, Lebanon, IN (US); **Mukund Jaganmohan**, Chennai (IN); **David Ochoa**, Boynton Beach, FL (US); **Bhaskara Rao Polisetty**, Nellore (IN)
(73) Assignee: **Caterpillar Inc.**, Peoria, IL (US)
(**) Term: **15 Years**
(21) Appl. No.: **29/854,050**
(22) Filed: **Sep. 21, 2022**

Related U.S. Application Data

(57) **CLAIM**

The ornamental design for a display screen or portion thereof with graphical user interface as shown and described.

DESCRIPTION

FIG. 1 shows a display screen or portion thereof with graphical user interface showing our new design; and, FIG. 2 shows another embodiment thereof.

The peripheral dashed broken lines illustrate a display screen or portion thereof, and form no part of the claimed design.

The text illustrated in broken lines forms no part of the claimed design.

1 Claim, 1 Drawing Sheet
